DESIGN FOR A HYDROMETER

Harold W. Eden, Chicago, Ill., assignor to Triple-A-Specialty Company, Chicago, Ill., a corporation of Illinois

Application September 15, 1934, Serial No. 53,299

Term of patent 7 years

To all whom it may concern:

Be it known that I, Harold W. Eden, a citizen of the United States, residing at Chicago, in the county of Cook, State of Illinois, have invented a new, original, and ornamental Design for a Hydrometer, of which the following is a specification, reference being had to the accompanying drawing forming a part thereof, in which:

Figure 1 is a front elevation of the entire hy-

drometer, the upper portion being shown in dotted lines;

Fig. 2 is a front elevation of the nozzle; and

Fig. 3 is a side elevation of the nozzle.

I claim:

The ornamental design for a hydrometer as shown and described.

HAROLD W. EDEN.
